J. A. ERNST, JR.

GAME APPARATUS

Filed Sept. 27, 1921

Fig. 1.

UNITED STATES PATENT OFFICE.

JOHN A. ERNST, JR., OF RIDGEFIELD PARK, NEW JERSEY.

GAME APPARATUS.

Application filed September 27, 1921. Serial No. 503,529.

To all whom it may concern:

Be it known that I, JOHN A. ERNST, Jr., a citizen of the United States, and a resident of Ridgefield Park, in the county of Bergen and State of New Jersey, have invented a new and Improved Game Apparatus, of which the following is a full, clear, and exact description.

This invention relates to a game apparatus, and has for an object the provision of a novel form of game apparatus in which a game such as base ball is played and in which the success of the game depends largely upon the skill of the operator in the manipulation of the apparatus.

Another object resides in the provision of means whereby this game may be economically manufactured and whereby the playing of the game is made comparatively simple except for the development of skill in the play.

A further object resides in the provision of means whereby the progress of the game may be very easily and plainly recorded.

The invention is illustrated in the drawings, of which—

Figure 1 is a perspective view of the apparatus;

Figure 2 is a partial vertical section showing the various positions of one of the operating parts of the game;

Figure 3 is a transverse section taken through the game board; and

Figure 4 is an elevation of a means for recording the progress of the game.

The invention as shown in the drawings is a preferred form of my invention illustrating it in one of its most interesting applications, although it is to be understood that other applications of this idea of game, and other forms of apparatus and structure, may be adopted and still employ the same operative principle and remain with the spirit of the invention as set forth and claimed.

The game as illustrated comprises a support having a body portion 1. This support has a long narrow frame having side walls 2 and 3. Along the edges of the side walls, and preferably pivoted to the inner faces of these side walls, are a plurality of pivoted L-shaped members which I preferably call semaphores. These semaphores comprise a projecting portion 4, which normally projects a desired distance above the edge of the particular wall to which the

semaphore is pivoted, and a wing portion 5 extending at right angles to the projecting portion 4 and normally lying beneath the edge of the side portion and preferably resting on a support which, as shown, is the body portion or bottom 1 of the frame. This wing portion 5 is provided with a surface 6 extending in the same general direction as the wing portion but bent at right angles thereto. This surface 6 I prefer to designate as an exhibiting surface on which certain preferred designations may be placed. A flanged portion 7 is bent up from the main body portion of the semaphore and is spaced from the main body portion to provide a suitable support for a pivot pin 8 which is at its other end fastened to the side wall in any suitable manner. At one side of the projecting portion 4 is an extension 9 which is adapted, when the semaphore is in the dotted position shown in Fig. 2, to rest on the bottom of the frame, or any other suitable stop surface, and is so designed and constructed that when the projecting portion 4 is in this position the exhibiting surface itself will be in a substantially upright position visible above the edges of the side wall.

The distribution of the mass throughout the semaphore is such that the semaphore normally tends to remain in the full line position shown in Fig. 2, and will remain in the position shown in dotted line in Fig. 2 preferably only so long as it is positively held in this position by some other means. When released by this exterior means the semaphore will drop back by reason of its weight to the position shown in full lines in Fig. 2. In the disposition of the semaphores throughout the length of the side walls 2 and 3, it will be noted that I have shown the set of semaphores attached to one wall staggered with respect to the set of semaphores attached to the other wall. This is for the principal reason that the means for operating the semaphores will operate only one at a time. This, of course, is only one preferred form of operation and it will be within the spirit of my invention to have more than one semaphore operated at one time, if desired.

To operate the semaphores, I have provided a traveler member, which as shown is in the form of a fly wheel 10 the body portion of which is pierced by suitable openings 11 and 12 to make the distribution of the mass non-uniform. This fly wheel is mount-

ed on a shaft 10, the ends of which project beyond the edges of the side walls 2 and 3. Since the distribution of the mass in this fly wheel is not uniform throughout, 5 the rotation of the fly wheel by any suitable means, such as the hand of the player, will make the attempt to cause the fly wheel to move a definite distance and then stop at this point a rather difficult procedure, and 10 this point is one wherein the skill of the operator will be called upon and which will tend to maintain the interest of the game by reason of the difficulty of being successful in the manipulation of the parts.

15 In the operation of the game, the player takes the ends of the shaft 11' in his fingers with the shaft resting on the upper edges of the side walls 2 and 3 at one end thereof, and twists the shaft to produce a forward 20 motion of the shaft and the fly wheel. The purpose in his mind is to cause the fly wheel, by reason of the motion imparted to it by him, to stop at a definite point, at which point the shaft has moved a particular 25 semaphore so that the exhibiting surface is in the upright position, and to cause this exhibiting surface to be maintained in this upright position by reason of the fact that the traveler has stopped so as to rest and 30 maintain depressed the projecting portion 4 in the position shown in dotted lines in Fig. 2. If the game being played is a game similar to the game of base ball the exhibiting surface 6 will be designated by such 35 designations as "Home run," "Third base hit," "Fly," and other similar designations; so that if the operator has in mind to be able to record a particular play it should be his intention, and his skill will be called 40 upon, to cause the traveler to stop at a particular point which may be more or less distant from the starting point. If the traveler should pass beyond the last pivoted 45 semaphore, a pair of grooves, such as 2' and 3' are provided in the upper edges of the side walls 2 and 3 into which the shaft 11' may drop to stop the movement of the traveler.

50 In order to record the progress and the score of the game as it proceeds, I have provided an indicator as shown in Fig. 4. This comprises a pair of plates the main portion of which is shown simulating a base ball diamond 13. These plates are of similar 55 shape and connected together by any suitable means. The lower portion of the indicator is provided with wing portions 14 and 15. The main body portion is marked out to simulate a base ball diamond with the 60 base line 16. At the points of the plates on the diamond opposite the bases the indicator plates are cut out, as at 17, and adjacent these points, on pins or rivets such as 18, a plurality of disks are mounted. These disks 65 are formed of sections, such as 19, which are

preferably colored, and 20, which are preferably plain. By moving the disks so that the colored portion 19 will show through the openings or apertures 17, the presence of the runner on the base will be indicated; 70 whereas if the disk is moved to present the plain uncolored portion, the absence of a runner on the base will be indicated. Other disks, such as 21, 22 and 23, may be used in the well known manner to indicate 75 "Balls," "Strikes" and "Outs."

It is also within the province of my invention to provide any suitable means (not shown) and to form the semaphores in such manner that as one is passed over by the 80 traveler member and raised to an elevated position, the distribution of mass may be such that it will remain in this elevated position but be moved back to its normal position by the next semaphore when that next 85 semaphore is operated by the traveler, the length and dimensions of each semaphore being such that as the wing portion of one is raised it will contact with the projecting portion of the other to move that other back 90 to normal position. The material of which this game apparatus is constructed is, of course, immaterial; any suitable substance which may be desirable to the person manufacturing and selling the device may be 95 used.

What I claim is:

1. A game apparatus which comprises a support, a pivoted semaphore member connected to said support, one arm of said semaphore normally projecting above the edge of the support, means moving upon the edge of said support to contact with the projecting arm and depress the same, and a second arm on said semaphore normally disposed below the edge of the support and adapted to be elevated when the projecting arm is depressed by said means, the mass distribution of said semaphore being so disposed as to cause the return of the semaphore to normal position as soon as the projecting portion is released by said means.

2. A game apparatus which comprises a long, narrow frame having side walls and a plurality of semaphore members pivoted to each wall, portions of said members extending above the upper edge of said wall, the semaphore members on one wall being staggered with respect to the members on the other wall, and a movable member extending from wall to wall and generally at right angles to the length of said wall, said member movable along the walls and successively engaging the portions of the semaphore extending above the walls, whereby 120 said semaphores may be actuated.

3. A game apparatus which comprises a frame having side walls, a plurality of L-shaped semaphore members pivoted to each of said walls, a portion of each semaphore 130

- projecting above the edge of the wall, an exhibiting surface or wing on each semaphore disposed normally below the edge of the wall, and means moving upon the edge 5 of the wall to contact with and depress the projecting portion of each semaphore to exhibit the exhibiting wing, the mass distribution of each semaphore being such that the semaphore will return to normal position as soon as the projecting portion is released by the movable means.
4. A game apparatus which comprises a frame having side walls, semaphore members disposed in association with said walls 15 and having portions extending above the edges of said walls, a shaft adapted to roll along the upper edge of said walls to engage the said portions of the semaphore members, a fly wheel mounted on said shaft 20 to provide momentum to the movement of said shaft, said fly wheel having cut-away portions therein, said cut-away portions being so disposed as to make the distribution of the mass of the fly wheel non-uniform, 25 whereby the movement of the shaft is rendered decidedly irregular and uncertain.
5. A game apparatus which comprises a frame having spaced walls, semaphore members on the said walls and having projecting 30 portions extending above the edges of said walls, exhibiting portions on said semaphore members lying normally below the edges of the walls, and means adapted to be moved by the player of the game upon the edges 35 of the walls to contact and depress the pro-
- jecting portions of the semaphore during its movement, the movement of travel of said means being dependent upon the amount of force supplied by the operator, the mass distribution of each semaphore being such 40 that its projecting portion remains depressed only so long as it is held down by the movable means.
6. A game apparatus which comprises a long narrow frame having lateral walls, a plurality of semaphore members pivoted to each wall, the semaphore members on one wall being staggered with relation to the semaphore members pivoted to the other wall, one arm of each semaphore projecting 45 above the edges of the adjacent walls, another arm of each semaphore normally disposed below the edges of the walls and having proper designations thereon, a shaft to be rolled upon the upper edges of the walls 50 by force applied by the player of the game, and a fly wheel disposed on said shaft to give it momentum, said fly wheel having cut-away portions therein to make its movement more irregular, the projection portions 55 of the semaphores adapted to be moved and depressed by contact with said shaft as it moves along the upper edges of the wall, said depressing movement causing an elevation of the exhibiting surfaces, the mass distribution of each semaphore being arranged 60 to cause the semaphore to return to normal position except when the projecting portion is being held depressed by the shaft.

JOHN A. ERNST, JR.
